UNITED STATES PATENT OFFICE.

FRANK E. BRAILE, OF SHAMROCK, OKLAHOMA.

ADJUSTABLE FOLLOWER-BLOCK FOR OIL DRILLING AND PUMPING RIGS.

1,341,968.

Specification of Letters Patent.

Patented June 1, 1920.

Application filed August 29, 1919. Serial No. 320,626.

To all whom it may concern:

Be it known that I, FRANK E. BRAILE, a citizen of the United States, residing at Shamrock, in the county of Creek and State 5 of Oklahoma, have invented certain new and useful Improvements in Adjustable Follower-Blocks for Oil Drilling and Pumping Rigs; and I do hereby declare the following to be a full, clear, and exact description of the same, reference being had to the accompanying drawings, forming part of this specification.

This invention relates to wrist pin followers, and particularly to followers that 15 are used in connection with the wrist pin and pitman of oil drilling and pumping rigs.

At present, in practically all oil drilling and pumping rigs the pitman is of wood 20 and is provided with an elongated rectangular slot, usually termed the follower slot, in which the wrist pin is journaled. One part of the bearing for the pin is in one end of the follower slot and the other part 25 of the bearing is in the face of a hard wooden block inserted in the follower slot and adjustably held in place by a second, wedge-shaped piece of hard wood, called the key, driven in a second slot formed in the pit- 30 man at right angles to the axis of the wrist pin bearing. This construction is objectionable in several particulars, namely, the pitman has to have a second slot cut there- 35 through for the key, thereby weakening the pitman, and, due to the constant jarring of the walking beam and pitman during both drilling and pumping operations, the key quite often becomes loose and is displaced from its slot, thus releasing the follower 40 block, causing the beam to jar or pound dangerously, and, unless the power is im- 45 mediately shut off, the pitman will leave the wrist pin and fall through the floor, breaking the sucker rods, if in use on a pumping well or causing more or less trouble in a 50 drilling well, depending upon the operation upon which the driller is engaged at the time.

With the foregoing defects of the present general construction in view, the objects of the present invention are, first, the provision of an adjustable follower block which dispenses with the key and key slot and which, together with its associated 55 parts, can be made of a single size adapted to be readily, quickly and securely applied

to the pitman of practically any of the oil drilling and pumping rigs now in use and, second, when the follower block is properly adjusted in the follower slot it can 60 be locked in such position against accidental displacement.

In the accompanying drawings,

Figure 1 is a front elevation of a portion of a pitman showing the follower slot with 65 the wrist pin and follower block positioned therein.

Fig. 2 is a sectional view taken on the line 2—2, Fig. 1.

Fig. 3 is a rear plan view of the pitman 70 as shown in Fig. 1, the crank pin being removed to permit a better illustration of the essential parts.

Fig. 4 is a detail sectional view on the line 4—4, Fig. 1.

The pitman 10, which generally in oil pumping and drilling rigs is of wood, is provided with a longitudinally extending, rectangular slot 11, called the follower slot. One end wall of slot 11 is provided 80 with a semi-circular bearing surface 12 which in conjunction with a similarly shaped bearing surface 13 on one of the filler blocks, presently to be described, forms a bearing in which is journaled the wrist pin 14 85 mounted in the crank 15. The bearing surface 13 in the filler block is provided with a recess 16 for lubricant which can be supplied thereto through a duct 17 extending from the recess through said block to the 90 exterior surface of the latter.

The follower block of the present invention consists of two hard wood filler blocks 95 18, 19, positioned in the follower slot 11 and adapted to be moved longitudinally thereof to permit them to be adjusted to any desired position, block 18 abutting the wrist pin at one end of the slot 11 and block 19 abutting the opposite end wall of said slot when the several parts are properly adjusted.

Filler blocks 18, 19 have their proximate faces 20, 21 inclined with respect to each other, face 20 of block 18 preferably lying in a plane parallel to the axis of the wrist pin bearing and when the blocks are being 105 assembled in the follower slot they are spaced apart a sufficient distance to permit a wedging member 22 to be entered a short distance between them, further inward movement of the wedge being obtained in a 110 manner to be presently described.

Wedging member 22 is provided with a

threaded bolt hole 23 in which works a threaded bolt 24 extending through the follower slot between the blocks 18, 19, with its longitudinal axis parallel to the axis of the wrist pin bearing. This bolt 24 projects through and is held against movement longitudinally of its axis by a metal plate 25 rigidly secured to a fixed portion of the structure, in the present instance it being shown secured to the filler block 18 by a plurality of screws although, if desired, it may extend laterally of the pitman across the follower slot 11, taking its bearing against the face of the pitman.

15 Obviously by rotating bolt 24 in the proper direction the wedge 22 will be drawn in between filler blocks 18, 19, and the latter moved longitudinally of the pitman slot into contact with the wrist pin and opposite 20 end wall of the slot, respectively.

By mounting the wedge block 22 and bolt 24 so that the former moves in a line parallel to the axis of the wrist pin, the wedge may be inserted between the filler blocks 25 through the open side of the slot 11 and the provision of a second or key slot in the pitman is rendered unnecessary. Furthermore, the filler blocks being adjustable longitudinally of the slot, they, with the wedge, may 30 be utilized in a follower slot of practically any length, thus permitting the manufacture of a follower block (and its associated elements) of one size only that can be placed upon the market for sale to replace the follower block originally sold with the rig. Should the slot be unduly long a thick shim 35 or block of known construction may be used to reduce its length.

To prevent the wedge 22 accidentally 40 working off the bolt 23 means are provided for locking the bolt against rotation after the filler blocks have been positioned. Secured in a slot extending through the head of bolt 23, at right angles to the longitudinal axis of the bolt is a relatively broad, flat metal bar 26 adapted to lie close to the face of plate 25 and the face of the pitman. Extending through holes 27 in the pitman on opposite sides of plate 25 are two pins 50 28 adapted to engage bar 26 on its opposite sides, each of said pins 28 being provided with a broad flat head offset from the center of the pins so as to overlap the face of bar 26. The two pins prevent rotation of the 55 bolt in either direction. The front and rear faces of the pitman are chambered out around holes 27 to allow the pins 28 to be pushed in flush with the face of the pitman when the bolt is to be manipulated and then 60 pushed out from the rear to catch bar 26 after the follower has been adjusted.

What is claimed is:

1. In an oil pumping or drilling rig, the combination with the pitman having a rectangular follower slot therein, of a wrist pin

adapted to be journaled in said slot and a follower comprising a pair of filler blocks removably and slidably mounted in the follower slot, one of said blocks having a bearing therein for the wrist pin, and means 70 movable in one direction only parallel to the axis of the wrist pin journal for adjusting said follower blocks longitudinally of the follower slot to compensate for wear on the wrist pin bearing, said filler blocks and 75 adjusting means being removable from the slot as a unit.

2. In an oil pumping or drilling rig, the combination with the pitman having a rectangular follower slot therein, of a wrist pin 80 adapted to be journaled in said slot and a follower comprising a pair of filler blocks removably and slidably mounted in the follower slot, one of said blocks having a bearing therein for the wrist pin, and removable 85 means movable in one direction parallel to the axis of the wrist pin journal for adjusting said follower blocks longitudinally of the follower slot to compensate for wear on the wrist pin bearing, and movable in the 90 opposite direction to permit removal of the filler blocks from the follower slot, and means for locking said blocks in adjusted position.

3. In an oil drilling or pumping rig, the combination with the pitman having a rectangular follower slot therein, a wrist pin, and a wrist pin follower comprising a pair of filler blocks adapted to be moved longitudinally of the slot, one end wall of said 100 slot and the adjacent face of one of the filler blocks having a bearing formed therein in which the wrist pin is journaled, and the adjacent faces of the filler blocks being inclined with respect to each other, and a wedge 105 member movable between the inclined faces of the follower blocks parallel to the axis of the wrist pin journal for adjusting the filler blocks longitudinally of the slot to compensate for wear on the wrist pin bearing, detachable means supporting the wedge member, said wedge member and filler blocks being removable from the follower slot, and means for locking said blocks in adjusted position.

4. In an oil drilling or pumping rig, the combination with the pitman having a rectangular follower slot therein, a wrist pin adapted to be journaled in the follower slot, and a wrist pin follower comprising filler 110 blocks adapted to be moved toward and away from each other in the follower slot, and means movable parallel to the axis of the wrist pin journal for adjusting the filler blocks toward and away from each other to compensate for wear on the wrist pin, said filler blocks and adjusting means being removably secured in said slot, and a detachable supporting member for the adjusting means.

5. In an oil drilling or pumping rig, the combination with the pitman having a rectangular follower slot therein, of a wrist pin and a wrist pin follower comprising a pair 5 of filler blocks adapted to be moved toward and away from each other in the follower slot, one end wall of said slot and the proximate face of one of the filler blocks forming a bearing in which the wrist pin is journaled 10 and the adjacent faces of said blocks being inclined with respect to each other, a screw threaded bolt extending through the follower slot parallel to the axis of the wrist pin journal, detachable means supporting 15 said bolt, and a wedge member positioned between the inclined faces of the filler blocks and having a screw-threaded aperture therethrough for coöperation with the bolt whereby said wedge member is movable parallel to 20 the axis of the wrist pin journal to adjust the filler blocks toward and away from each other to compensate for wear on the wrist pin bearing.

6. A wrist pin follower block for the pit-

man of oil drilling and pumping rigs comprising filler blocks movable toward and away from each other in the follower slot of the pitman, means for adjusting said blocks toward and away from each other to compensate for wear on the wrist pin bearing, and detachable means structurally independent of the pitman for supporting said adjusting means in engagement with the filler blocks.

7. A compensating bearing for the wrist 35 pin engaging pitman of a well drilling rig, embodying a pair of blocks, one having a semi-cylindrical bearing for the wrist pin and the proximate faces of said blocks being relatively inclined longitudinally of the axis 40 of the bearing, a wedge between the proximate faces of the blocks, a screw for adjusting the wedge longitudinally of the axis of the bearing and an abutment carried by one 45 of the blocks and fixed with relation to the blocks and with which the screw coöperates in effecting the adjustment of the wedge.

FRANK E. BRAILE.
